UNITED STATES PATENT OFFICE.

CALEB S. PARRIS, OF BOSTON, MASSACHUSETTS.

FIRE-ESCAPE.

1,163,032.

Specification of Letters Patent.

Patented Dec. 7, 1915.

Application filed March 18, 1914. Serial No. 825,690.

To all whom it may concern:

Be it known that I, CALEB S. PARRIS, a citizen of the United States, residing at Boston, county of Suffolk, State of Massachusetts, have invented an Improvement in Fire-Escapes, of which the following description, in connection with the accompanying drawing, is a specification, like characters on the drawing representing like parts.

10 This invention relates to improvements in fire escapes of the type in which a stairway leads from accessible exits from the upper floors of a building to the ground. Such fire escapes are usually secured to the outer 15 wall of the building and are provided with means whereby the lowest section of the stairway may be lifted above the ground a sufficient distance to prevent intruders from obtaining access to the building by way of 20 the fire-escape, the lowest section being adapted to be lowered from above to permit persons escaping from a fire to descend to the ground. The fire escapes thus constructed are exposed to the weather and often are 25 used to support rugs, mattresses, etc., while they are being cleaned so that not infrequently the mechanism which supports the lowest section of the fire escape becomes clogged and cannot be readily released by 30 persons escaping from a fire in the building.

In some types of fire-escapes the lowest section of stairway is so balanced that it is supported in substantially a horizontal position by the heavier weight of the upper 35 end of the section or by a weighted extension thereof. In such cases a person may walk a considerable distance out upon the other end of the lower section before it is overbalanced and its rapid movement thereafter 40 will be likely to hurl the person to the ground with violence. In other cases the mechanism for locking the lower section in horizontal position is so located that a person escaping from the fire may immediately 45 step upon the upper part of the lower section after releasing the locking member and the rapid descent of said lower section with the weight of the person on it will throw him to the ground.

50 One object of this invention is to provide a simple but effective means whereby a person escaping from a fire will actuate the releasing mechanism in passing from the landing at the upper end of a flight of stairs above 55 the lowest or cantaliver section so that the

free end of the lever will be permitted to descend to the ground before the person reaches the topmost step thereof.

Another object of the invention is to provide a locking mechanism for the pivotally 60 mounted cantaliver section which will not become clogged or set by ice, dirt or other obstructions of like character.

In a preferred embodiment of the invention illustrated in the drawings, Figure 1 is 65 a side elevation of the lower sections of the fire escape showing the second floor landing or balcony, a short flight of stairs descending therefrom and a cantaliver section balanced at the foot thereof, Fig. 2 is a front 70 elevation of the same, and Fig. 3 is a detail elevation broken away in the middle of the supporting and releasing mechanism for the cantaliver. Fig. 3 is a detail view of the locking and releasing mechanism illustrated 75 in Figs. 1 and 2.

The preferred form of fire escape embodying this invention comprises a series of iron or steel stairways, (not shown) leading from the upper stories of the building with landings at the various floors connecting therewith such as that illustrated herewith with an exit on the second floor. These landings are desirably constructed of a grated floor section formed of iron rods or tubes which 80 are suitably connected at their ends by cross members 2 and rest upon horizontally disposed supporting members 3 anchored in the wall of the building and which may be provided with downwardly inclined metallic 85 braces 4. The landing or balcony is desirably provided with a grating or railing 6 of sufficient height to prevent persons hastening from the exit from accidentally falling from the landing. The second floor landing 90 leads to a flight of steps 7 preferably consisting of steel supporting girders connected by iron rods or slotted metallic steps 8 and terminating a sufficient height above the ground to render it impossible for a person 95 standing on the ground to reach the same. The lower end of the flight is supported upon a strong preferably cylindrical bar 9 anchored in the wall of the building and desirably provided with a supporting brace 100 10. Suitable guard rails 11 and posts 12 may be provided to strengthen the structure and to prevent descending persons from falling over the sides of the flight 7.

The lowermost section of the fire escape 110

comprises a cantaliver section constructed of steel girders 13 pivotally mounted upon the bar 9 outside of the planes of the girders of the stationary flight 7. The girders 13 are extended beyond the pivotal rod 10 to points vertically beneath the second floor landing and are connected upon their undersides by cross pieces 17 provided with means for supporting suitable weights 18 adapted to nearly counterbalance the lower section of the cantaliver. The girders 13 are connected below the pivotal bar 10 by the usual series of steps constructed in the manner aforesaid.

As above stated one of the principal objects of the present invention is to provide a simple and effective means for supporting the cantaliver in lifted or horizontal position which may be released easily and certainly by a person escaping from the fire as he leaves the upper landing so that by the time he reaches the lower end of the inclined section which leads to the cantaliver the foot of the ladder will have reached the ground so that he may descend in safety.

In the preferred form of invention disclosed in the drawing this is accomplished by providing a latch for the cantaliver section comprising a vertical shaft 19 suitably journaled in bearings 20, 21, in members secured to and extending laterally from an upright or post 23 at the outer corner of the landing adjacent to the inclined section 7, the shaft 19 being provided with collars 24, 25 adjustably secured thereon by suitable set screws. The collar 24 is desirably secured upon the shaft 19 to bear upon the underside of the bearing 20, and the collar 25 is so secured to the rod 19 as to bear upon the upper surface of the bearing 21 thereby preventing longitudinal movement of the rod 19 in either direction. The rod 19 may be provided at its lower end with lateral extensions 26, 27 adapted to be positioned so as to embrace the outer girder of the cantaliver section when the latter is raised to horizontal position and to lock the same in said position against movement in either direction.

The shaft 19 is desirably made of sufficient length to permit its end to be bent laterally in substantial parallelism with lateral extensions 26 and 27 to form a gate or barrier 28 across the exit passage leading from the second floor landing to the flight 7. It is found in practice that the engagement of the arms 26, 27 with the girders 13 of the cantaliver is sufficient to prevent accidental rotation of the shaft 19 and it is desirable to avoid as much as possible the use of any obstructing means which would be likely to delay a person in his escape from the fire. If found desirable however the free end of the gate member 28 may be caused to rest in a depression in a plate 29 carried by the top rail of the grating 6 or

any other suitable latch mechanism which may be easily and certainly released.

In the operation of the device the first person fleeing from the fire by way of the fire escape must release the gate or barrier before he can descend the inclined flight 7 leading to the outer end of the cantaliver section. This is easily accomplished by merely pressing against, or at most, slightly raising and pressing against the gate 28. As he passes on the gate will swing aside rotating the shaft 19 and the members 26 and 27 from engagement with the girder 13 thus permitting the foot of the cantaliver to descend. The lower end of the cantaliver being of slightly greater weight than its upper end will descend with sufficient rapidity to permit its foot to rest upon the ground by the time the fleeing person has reached the upper end of the cantaliver section so that his progress to the ground will be unimpeded.

The cantaliver may be restored to horizontal position by raising the foot thereof by means of a pole or other convenient device and may be locked in that position by restoring the gate to its normal position across the floor of the second landing.

Having thus described my invention what I claim as new and desire to secure by Letters Patent is:

1. A fire escape comprising a landing, an inclined stairway leading therefrom and terminating at a point well above the surface of the ground, a cantaliver pivotally mounted at the lower end of said inclined stairway provided with a flight of steps adapted to lead from said stairway to the ground and an extension weighted to nearly balance said flight of steps, a rotatably mounted vertical shaft depending from said landing and having at its upper end a member operable from said platform and at its lower end a laterally extended member adapted to engage the extension of said cantaliver to hold the cantaliver in elevated position.

2. A fire escape comprising a landing, an inclined stairway leading therefrom and terminating at a point well above the surface of the ground, a cantaliver pivotally mounted at the lower end of said inclined stairway and provided with a flight of steps adapted to lead from said stairway to the ground, an extension counterweighted to nearly balance said flight of steps, a vertical shaft rotatably mounted in bearings carried by said landing and having at its lower end a pair of laterally extending members adapted to engage the extension of said cantaliver and hold the cantaliver normally in elevated position, and at its upper end an arm extending laterally in parallelism to said cantaliver engaging members, and adapted to form a barrier across the exit of

said landing whereby a person fleeing from a fire must necessarily release the cantaliver before descending the inclined stairway, thus permitting the end of the cantaliver 5 to descend and rest upon the ground before the person reaches the upper end of said flight of steps.

In testimony whereof, I have signed my name to this specification, in the presence of two subscribing witnesses.

CALEB S. PARRIS.
